UNITED STATES PATENT OFFICE.

ABRAHAM BECKELMAN, OF NEW YORK, N. Y.

DETACHABLE HEEL.

1,175,684.

Specification of Letters Patent. Patented Mar. 14, 1916.

Application filed April 16, 1915. Serial No. 21,733.

To all whom it may concern:

Be it known that I, ABRAHAM BECKELMAN, a citizen of the United States, and a resident of the city of New York, borough 5 of the Bronx, in the county of Bronx and State of New York, have invented a new and Improved Detachable Heel, of which the following is a full, clear, and exact description.

10 This invention relates to heels for shoes and particularly to what is known as a detachable heel, and has for an object the provision of an improved arrangement of securing means whereby the heel may be 15 quickly and easily applied and removed and when applied will be held rigidly in place.

Another object in view is to provide a detachable or removable heel section and means for holding the same in place, the arrangement being such that a single retaining member 20 is sufficient.

Another object of the invention is to provide a removable or detachable heel section and arrange a reinforcing member therein 25 which will assist in retaining the heel in place when in use.

In the accompanying drawings:—Figure 1 is a fragmentary sectional view through part of a shoe and heel embodying the invention; Fig. 2 is a bottom plan view of the heel shown in Fig. 1; Fig. 3 is an inverted perspective view of the removable section of the heel shown in Fig. 1; Fig. 4 is an inverted perspective view of the heel in a detached or open position; Fig. 5 is a section through Fig. 4 on line 5—5.

Referring to the accompanying drawings by numerals, 1 indicates a shoe of any desired kind provided with a heel section 2 of 40 substantially the usual construction. Connected to the heel section 2 is a plate 3, the same being held in place by any suitable means, as for instance a number of screws 4. A heel section 5 of rubber is adapted to be 45 arranged on section 2, as shown in Fig. 1, and held in place by a securing bolt 6, which bolt extends through plate 3 and through part of section 5 so as to receive the retaining nut 7. It will be observed that the bolt 50 6 is provided with a squared section 8 so that the bolt cannot rotate, and that nut 7 is formed square so that the corners 9 will project into the rubber section 5, as shown more particularly in Fig. 2. This will prevent any accidental loosening of the nut.

The section 5 is formed with a plurality

of depressions or vacuum cups 10 for assisting in preventing slipping. It will be noticed, especially in Fig. 3, that the rubber section 5 is provided with a flexible reinforcing plate 11 which is bowed both longitudinally and transversely. There is arranged a small section 12 of rubber between nut 7 and the reinforcing plate 11 whereby the plate is not exposed to the weather and 65 other undesirable conditions.

The plate 3 secured to section 2 is formed of any desired material, as for instance metal, and is of an appreciable thickness so as to fit into the recess or socket 13 in the section 5 and act as means for preventing the rotation of said section. This is very desirable as there is only one retaining member, namely, bolt 6, which would not be sufficient to prevent the rotation of section 5. It 70 is evident that the plate 3 could be of any suitable size but must fit with reasonable accuracy the recess 13 so as to insure the section 5 against movement.

It will be observed that there is no adhesive for holding the rubber section in place and that there is provided only one retaining member, namely, bolt 6, which may be easily operated whenever desired but which cannot readily become loose. By this 85 construction and arrangement the section 5 may be applied and removed whenever desired by any one. Preferably a special wrench is provided for operating nut 7, the same being formed with two or four prongs 90 for fitting the sides of the nut in order that the same may be properly tightened. It is evident that either form of nut could be used without departing from the spirit of the invention. However, a nut having some 95 form of projecting corners 9 is desirable as the same insures against accidental removal of the nut.

What I claim is:—

1. In a heel of the character described, a 100 fixed or permanent section, a metallic plate fixed to said permanent section and projecting therefrom, said plate having a squared opening therein, a bolt having a squared portion, said bolt projecting through said opening in such a manner that the squared portion will fit said squared opening, a detachable resilient section fitting on said permanent section and arranged so that said bolt will project partially therethrough, 105 said detachable section having a recess for accommodating said plate, and means en-

gaging said bolt for clamping said resilient section in position, said means being formed with projections extending into said resilient section and thereby locked against accidental movement.

2. In a heel of the character described, a fixed or permanent section, a metallic plate secured to said fixed or permanent section, a detachable resilient section, said detachable resilient section being provided with a metallic reinforcing plate embedded therein and with an aperture extending therethrough including said metallic plate, a clamping screw held in place by the plate secured to the fixed section extending partially through said resilient section, said

screw being arranged in the aperture in said resilient section, and a nut having corners arranged in said aperture so that the corners will project into the material of said resilient section while the nut is threaded on to said screw, the material of said resilient section preventing the reverse rotation of said nut.

In testimony whereof I have signed my name to this specification in the presence of two subscribing witnesses.

ABRAHAM BECKELMAN.
